[57] ABSTRACT

A front rail constituting a key frame for supporting the keys of a piano comprises a plurality of rectangular wooden blocks connected end to end to form an elongated rail body, and a surface covering member of synthetic resin material securely attached to at least the entire upper surface of the rail body. The surface covering member serves to protect the rail body from being affected by the humidity conditions, so that the front rail is subjected to less warping deformation. Other surfaces of the rail body may also be covered by the surface covering member so as to completely prevent moisture from causing the front rail to be warped.

KEY FRAME CONSTRUCTION FOR PIANOS AND LIKE MUSICAL INSTRUMENTS

DETAILED DESCRIPTION OF THE INVENTION

This invention relates to a key frame for supporting the keys of a piano or the like musical instruments, and more particularly to a key frame construction comprising a rail member which is free from warping deformation as would be caused by variations in the moisture condition of surrounding atmosphere.

A piano keyboard assembly is generally located above a main rail on which the moving parts of the action are supported and comprises a plurality of keys pivoted on a key bed or board mounted on the piano case or frame. Each key is fulcrumed on a balance rail of a key frame supported on the key bed. The balance rail is disposed between front and rear rail members in spaced relationship therewith and connected thereto by a suitable number of transverse members or slats.

The inner end of each key is limited in its lowermost position by a felt pad or stop provided on the rear rail member while the outer end is in alignment with the front face of the front rail member.

It has been the conventional practice to form the front and intermediate balance rails of the key frame from wood material. However, wood has a disadvantage that it is susceptible to influences of moisture contents in the surrounding atmosphere. The conventional key frame has a body structures of its front, balance and rear rail members formed from a single piece of wood and therefore is easily deformed when there occur variations in the environmental moisture conditions. The warping deformation of the key frame, especially of the front rail member, causes irregular positional displacements to the keys supported thereon with the result that the keys cannot be maintained in uniformly spaced relationship on a horizontal plane. Furthermore, the irregular positional displacement of the keys must be prevented strictly since they would otherwise be caused to lose balance during pivoting movements thereof. It is considered that the warp curving of the front, balance or rear rail member is caused essentially by a difference in moisture content between the upper surface portion of the rail body structure and the lower surface portion which is closely in contact with a supporting bed or board.

In order to avoid the warp curving, the front or balance rail member may be formed entirely from a synthetic resin material which has no or less moisture absorbing property. However, with a synthetic resin front or balance rail construction, it will be made difficult to securely anchor and retain the front or balance pin members therein. Furthermore, the synthetic resin material is not suitable for forming key frame rails as it has too much rigidity and would not congruously fit on the wood board member on which the key frame is supported.

This invention therefore contemplates to provide an improved key frame construction which will eliminate the above difficulties.

It is the primary object of the invention to provide an improved key frame construction for pianos or the like musical instruments, which construction is free from warping deformation and has a rigidity congruous with the wood board member on which the key frame is supported.

It is another object of the invention to provide a key frame of the type mentioned above and which key frame is simple in construction, easy to manufacture and capable of maintaining the pin members securely anchored therein.

According to one feature of the invention, a key frame for a piano or like musical instruments including front and balance rail members spaced apart from each other and supporting a plurality of keys thereon, at least one of the rail members comprising a plurality of wooden blocks connected end to end to form an elongated rail body, and a surface covering member of synthetic resin material securely attached to the rail body.

According to another feature of the invention, that surface of the rail body facing the keys may be covered with the surface covering member of synthetic resin material.

According to still another feature of the invention, the opposite surface of the rail member to that facing the keys may be covered with the surface member of synthetic resin material.

The above and other objects, features and attending advantages of the invention will become apparent from the following description when taken in conjunction with the accompanying drawings which illustrate by way of example of one preferred embodiment of the invention, and wherein:

FIG. 1 is a schematic side view of the key frame construction according to the present invention; and

FIG. 2 is a fragmentary perspective view showing, on an enlarged scale and in more detail, the front rail body structure and the manner in which the front pins are supported on the front rail.

Before explaining the present invention in detail, it is to be understood that the invention is not limited in its application to the details of construction and arrangement of parts illustrated in the accompanying drawings, since the invention is capable of other embodiments and of being practiced or carried out in various different ways. Also, it is to be understood that the phraseology or terminology employed herein is for the purpose of description only and not of limitation.

Referring to the drawings, a more detailed description of the instant invention will be given. FIG. 1 shows in side elevation a piano key frame construction embodying the present invention and generally indicated by reference numeral 1. The key frame construction includes, same as in the conventional counterparts, a front rail member 4 and a rear rail member 6 disposed in parallel spaced relationship with the front rail member 4. Interposed between the front rail member 4 and the rear rail member 6 is an intermediate or balance rail member 5 having balance pin members 9 securely anchored therein. The front rail member 4, intermediate or balance rail member 5 and rear rail member 6 are connected together by transversely extending slat member of which only the endmost one is shown at 3 in FIG. 1. The slat members 3 are disposed perpendicular to and at a predetermined distance along the length of the three rails 4, 5 and 6. A plurality of keys 7 are pivotally supported on the balance pin members 9 in uniformly spaced relationship. The inner end of each key is limited in its lowermost position by a felt pad or stop 10 while the top inner end of the key is provided with a capstan screw 15.

According to the invention, the front rail member 4 with front pin members 8 on the upper surface has an

elongated body structure 12 consisting of a plurality of (usually 4 through 10) rectangular wood piece or block members 11 of a same thickness connected end to end and sandwiched securely between two relatively thin plate members 13 and 14 each formed from synthetic resin material such as acrylonitrile-butadiene-styrene resin material. The plate or surface covering members 13 and 14 are applied coextensively to the upper and lower surfaces of the front rail body structure 12 with use of a suitable adhesive agent or compound. The synthetic resin plate member 13 is preferred to have a thickness from one to two millimeters so as to facilitate passage therethrough of the front pin members 8. The front pin members 8 are securely anchored into and retained in the wood block members 11 at the respective root end portions which are passed through the upper covering plate member 13. When forming the front rail body structure 12, the wood block members 11 are orientated such that their grains run in the longitudinal direction of or along the length of the body structure 12.

With the front rail construction as described above, the upper surface of the front rail body structure 12 is covered with the synthetic resin material 13 so that there will be little or no possibility of the front rail member 4 being warped as a result of moisture absorption through the upper surface portion of the front rail body structure 12. It is important to note that even if the individual wood block members 11 are subjected to warping deformation, deformation of the front rail member as a whole may be much less than the conventional counterparts where the front rail body structure is formed from a single piece of wood. In addition to the resistance to deformation, the front rail construction of the invention has a moderate rigidity so that it congruously fits on the board or bed on which the key frame is supported. The synthetic resin plate member 13 covering the upper surface of the front rail body structure 12 is made thin enough to allow the front pin members 8 to be planted easily therethrough securely into the underlying wood block members 11. It will be appreciated from the foregoing that according to the invention the key misalignment or displacement which has been experienced due to warp curving of the front rail member may be completely avoided and the front pin members may be securely held in position.

In the embodiment described above, the front rail member 4 is shown as having both the upper and lower surfaces thereof covered with synthetic resin material 13 and 14. However, the lower surface of the front rail body structure 12 may not necessarily be provided with the covering plate member 14 since the lower surface is held in close contact with the supporting board or bed 2 and thus less influenced by environmental moisture conditions. On the other hand, in order to eradi-

cate the moisture influence on the front rail member 4 completely, the front or outer and the rear or inner faces of the front rail 4 may also be covered by the surface covering members of synthetic resin material in a like manner as explained above, in addition to the upper and lower surfaces thereof. Needless to say, the intermediate balance rail 5 and the rear rail 6 may be constructed in a manner similar to the front rail in order to achieve the same warp preventing effects.

10 What is claimed is:

1. In a key frame for a piano or like musical instruments, including front and balance rail members spaced apart from each other and supporting a plurality of keys thereon, at least one of said rail members comprising a plurality of wooden blocks connected end to end to form an elongated rail body having a key-supporting surface and another surface opposite to said key-supporting surface, said key-supporting surface facing said keys, a surface covering member of synthetic resin material directly attached to said key-supporting surface, said surface covering member covering the entire area of said key-supporting surface, another surface covering member of synthetic resin material directly attached to said other surface, said other surface covering member covering the entire area of said other surface.

2. In a key frame for a piano or like musical instruments, including front and balance rail members spaced apart from each other and supporting a plurality of keys thereon, at least one of said rail members comprising an elongated rail body of wood having a key-supporting surface and another surface opposite to said key-supporting surface, said key-supporting surface facing said keys, a surface covering member of synthetic resin material directly attached to said key-supporting surface, said surface covering member covering the entire area of said key-supporting surface, another surface covering member of synthetic resin material directly attached to said other surface, said other surface covering member covering the entire area of said other surface.

3. In a key frame according to claim 1, wherein said surface covering members of synthetic resin material provide a rigidified sandwich construction with said wooden rail body while preventing moisture penetration therethrough to said intermediate wooden rail body to preclude warping of the latter.

4. In a key frame according to claim 2, wherein said surface covering members of synthetic resin material provide a rigidified sandwich construction with said wooden rail body while preventing moisture penetration therethrough to said intermediate wooden rail body to preclude warping of the latter.
